SHOE BOTTOM CEMENTING MACHINE

Wilbur L. MacKenzie, Beverly, Mass., assignor to
 United Shoe Machinery Corporation, Borough
 of Flemington, N. J., a corporation of New
 Jersey

Application June 25, 1940, Serial No. 342,284

7 Claims. (Cl. 12—80)

This invention relates to machines for treating shoe bottoms and is herein illustrated as embodied in a machine for applying a coating of cement to the overlasted margin upon the bottom of a shoe in which the sole is to be secured to the shoe chiefly by means of adhesive, and of the type shown in Letters Patent of the United States No. 2,100,341, granted November 30, 1937, upon my application.

In machines of the type shown in that patent, shoes are presented in inverted position to a depending nozzle by which a band of cement is applied to the overlasted margin in just the desired relation to the peripheral outline of the shoe, and the operator is assisted in causing the traversing movement of the shoe by a driven feed roll which engages the side of the shoe closely adjacent to the nozzle. It will be understood, however, that the relation between the bottom of the shoe and the side of the shoe varies radically between the forepart portion, where the side is more nearly normal to the bottom of the shoe, and certain other portions, notably those in the shank of the shoe where the relation changes from the rather flat condition found at the inside of the shank to a radically different condition at the outside of the shank. This means that the relation of the feed roll to the side of the nozzle must change as the periphery of the shoe bottom is traversed. One way of accommodating these differences in the relation of the feed roll and the nozzle is illustrated in the above-mentioned patent in which a carrier for the driven feed roll is supported so that it is laterally yieldable against the tension of a spring.

With this in mind, an object of the invention is to provide a simple and less expensive arrangement by means of which the same result may be secured. As illustrated herein, and in accordance with features of the invention, the feed roll carrier is held in a position which is fixed with respect to the nozzle when the machine is in operation, and the changing relation of the side of the shoe is accommodated by providing a feed roll which is in nature quite like the balloon tire of an automobile; in other words, this feed roll is readily distortable and is capable of assuming various shapes which will permit it to provide firm feeding contact with the side of the shoe and, at the same time, to yield sufficiently so that the bottom of the shoe may be kept substantially horizontal in its desired relation to the nozzle during the whole traverse of the shoe bottom.

These and other features will best be under-

stood from a consideration of the following description, taken in connection with the accompanying drawings in which

Fig. 1 shows in side elevation, with a cover removed, the essential features of a bottom cementing machine including my novel construction;

Fig. 2 is a detail view on a much larger scale, showing the coaction of the feed roll with the shank portion of the shoe; and

Fig. 3 is a similar view, illustrating the coaction of the feed roll with the toe end of the shoe.

As in the patented machine, a nozzle 10 is supported upon a bracket 12 which is clamped to a rod 14 held by a set screw 16 in an arm 18. This arm 18 is pivoted upon a pin 20, and the nozzle may be raised slightly against the tension of a spring 22 when a shoe 100 (Fig. 3) is raised into engagement with the nozzle. The illustrated nozzle is constructed as shown in Letters Patent of the United States No. 2,177,666, granted October 31, 1939, upon the application of MacKenzie et al., and comprises a series of individually yieldable delivery members 24, these members being supplied through tubes 26 from a pipe 28 (Fig. 1) through which cement is delivered under pressure by means of a pump 30 from a receptacle 32. A valve 34 to control the flow of cement is arranged to be turned by an arm 36 joined to a treadle-operated lever 38 by means of a link 40. The connection between a treadle (not shown) and this lever comprises a treadle rod 42 and a link 44 having a lost-motion connection 46 for a purpose which will be later explained. When the treadle 38 is released, the valve is returned to closed position by means of a spring 48.

It is convenient to arrange for the withdrawal of a feed roll 50 from the immediate neighborhood of the nozzle 10, when no work is being presented to the machine, in order that there may be no soiling of the feed roll; and to this end, the feed roll is secured to a shaft 52 which is journaled in a carrier 54 pivoted upon a drive shaft 56 to which the shaft 52 is connected by a worm and worm wheel 58. Movement of the feed roll carrier 54 from the inoperative position illustrated in Fig. 1 to a position in which the feed roll engages the side of the shoe, as in Figs. 2 and 3, is effected by a bell-crank lever 60 pivoted upon the frame 70 and one end of said lever is connected to the upper end of the treadle rod and the other end is joined to the carrier 54 by a link 62. When the treadle is depressed, the feed roll is moved laterally to the left to a predetermined position dependent upon the engagement of an

abutment 64 upon this bell-crank lever 60 with a stop surface 66 formed upon the frame 70 of the machine.

In this improved construction, the feed roll 50 instead of being relatively solid, as in the prior machines, is made more like a balloon tire so that it is readily distortable, and, to this end, it comprises a casing 72 (Fig. 2) of soft rubber which is clamped between the end of the shaft and a plate 74 held in position by means of a screw 76. Both the hub of the shaft 52 and the plate 74 are grooved at 78 and 80 to receive ribs upon the casing 72 and hold the latter against pulling away from the shaft. This plate 74 is in a plane intersecting the side of a shoe close to the nozzle. Although it is evident that an inflated roll might be employed, a simpler and better construction is that illustrated herein, in which the casing 72 surrounds an annulus 82 of sponge rubber or the like. It will be noted that the portion of the feed roll 50 which is above the plane of the clamp plate 74 is less than that portion which is below it, and this arrangement permits of the radical distortion of at least the portion of the roll below this plane, such as is shown in Figs 2 and 3 when the feed roll is in engagement with the inside shank portion S' or the outside shank portion S'' of the side of a shoe 100.

In using the machine, the operator will first depress the treadle attached to the rod 42 thereby opening the valve 34 and moving the feed roll carrier 54 to its operating position, as shown in Figs. 2 and 3, whereupon the shoe is next presented in such a position that the nozzle 10 rests upon the overlasted margin M of the bottom of the shoe at a point near the heel breast line, and the shoe is then given a traversing movement with respect to the nozzle to cause the latter to coat progressively the shank portion of the shoe, the forepart and the toe end T, the shank portion on the other side of the shoe, and back again to the heel breast line. Since the carrier 54 for the feed roll 50 occupies a predetermined position in the machine during the presentation of a shoe, the operator learns readily to determine, largely by feeling, how hard the shoe must be pressed against the distortable feed roll 50 to cause the nozzle to apply a band of cement at just the required distance from the peripheral edge of the shoe, which is needed for the particular style of shoe under consideration.

Having thus described my invention, what I claim as new and desire to secure by Letters Patent of the United States is:

1. In a machine for treating progressively the marginal portion of the bottom of a shoe, a shoe-treating tool arranged to coat with the bottom of an inverted shoe, a feed roll journaled for rotation around an axis fixed with respect to the treating means, said feed roll comprising a soft annular member capable of yielding to accommodate all the variations in angular relation between the bottom of the shoe and an adjacent side portion of the shoe.

2. In a machine for applying cement to the overlasted margin upon the bottom of a shoe, cement-applying means arranged to coat with

the bottom of an inverted shoe, and driven feeding means journaled for rotation around an axis fixed with respect to the applying means, said feeding means comprising a soft roll capable of yielding to accommodate all the variations in angular relation between the bottom of the shoe and an adjacent side portion of the shoe.

3. In a bottom-cementing machine, means to apply cement to the overlasted margin upon the bottom of a shoe comprising a nozzle, and means for assisting the operator in traversing the work with respect to the nozzle comprising a feed roll for engagement with a side of the shoe, said roll being driven upon an axis held against lateral movement, and being yieldable in a direction laterally of the nozzle to accommodate the changing relation between the side of the shoe and an adjacent portion of the shoe.

4. In a bottom-cementing machine, a vertically yieldable support, a nozzle mounted on said support, means for supplying cement to said nozzle, a feed roll for engaging the side of the shoe adjacent to the nozzle, a carrier in which said feed roll is journaled, means for moving said carrier to transfer the feed roll from an idle position to a predetermined fixed position closely adjacent to the nozzle, said feed roll comprising a soft, yieldable periphery capable of distortion sufficient to care for the changing relation between the bottom of the shoe and a closely adjacent side portion of the shoe.

5. In a bottom-cementing machine, a nozzle for applying cement to the overlasted margin upon the bottom of a shoe, said nozzle being yieldable heightwise of the shoe, a carrier occupying a predetermined position laterally of the work-contacting end of the nozzle, a driven feed roll journaled in said carrier and arranged to carry the shoe along beneath the nozzle when the shoe is presented thereto by an operator, said feed roll being supported in a plane intersecting the side of the shoe close to the nozzle and having a distortable portion on the side of said plane away from the nozzle which will maintain firm contact with the side of the shoe both in the forepart and in the shank portions of the shoe.

6. In a bottom-cementing machine, means to apply cement to the overlasted margin upon the bottom of an inverted shoe, a driven feed roll journaled for rotation around an axis fixed with respect to the applying means, said feed roll comprising an annular tire-like casing substantially filled with a readily compressible material of the nature of sponge rubber whereby it is capable of yielding to accommodate the changing relation between the side of the shoe and the adjacent portion of the bottom of the shoe.

7. In a machine for treating the peripheral portion of a shoe, a feed roll adapted to engage the side of the shoe and driven to carry the shoe past the operating point, said feed roll having a supporting central web, and an annular ring joined to said web and providing a soft yieldable periphery capable of easy distortion, said annular portion being offset with respect to the web so that a majority of the work-engaging periphery lies at one side of the web.

WILBUR L. MACKENZIE.
